29.

Walter Lockling, of Sparta, State of New York.

Sollicited Patentee.

The schedule referred to in this Letter Patent is making part of the same, containing a description in the words of the said Walter Lockling himself, of his improvement in the apparatus for extracting smoke and vapor therefrom to be applied to Steam Boilers.

To all to whom these presents shall come

Be it known that I, Walter Lockling, of Sparta in the County of Livingston, in the State of New York, have invented a new and useful improvement in the method of extracting for combustion the smoke produced from the fire of an ordinary Steam Engine; and also for conducting the smoke from the smoke-pipe, either separately or together with the smoke, heat, &c. from the smoke-pipe into the reservoir; thereby producing a great economy of heat.

My invention relates to an improved construction of the apparatus, here to be used for that purpose, the nature of which has too much wherein the same is to be performed as fully as possible, and explained by the following description. The invention consists of an apparatus applied to the outlet of either, or both, of the pipes, used for the escape of the smoke, or of the steam, &c. so to produce a strong current of air, by means of a rotary bellows, which is constructed by affixing wings to a shaft revolvin in a rotatable case, taking care that they strike as near the air current as possible, and the shaft may be driven by any suitable application from the engine. The first invention, it will be necessary to give by later, small one side of the case, it will be found necessary in the bottom of the smoke-pipe so that the smoke may be driven by the current of air against the bottom of the pipe, and the pipe may be turned on the office

side, into a tube thirty of five, leading to the desired point, which is one that the smoke is to be burned, and by this bringing it into immediate contact with the fuel, so as to be drawn through it, But if the object were to carry it together with the escape steam, into the reservoir; then of course the escape steam pipe will also open into the rotary bellows, or the smoke pipe. Should it be desired to conduct them to different points, as for instance the smoke through the fire, and the steam into the reservoir, then have a rotary bellows with an arm sufficiently long to admit of a partition between or a division of the wings, thereby forming two chambers, one intended for the smoke, and the other for the steam. I would have it understood that I do not claim the combustion of the smoke, nor the return of it, and the escape steam, or the escape steam only; but what I do claim is the adaptation of the rotary bellows, according to the manner of construction above set forth, as a means of conducting the smoke or steam from the escape pipe ~~thence~~ to the point already designated in the engine.

In testifying that the above is a full description of my improvement, I have hereunto set my hand this fifth day of January in the year eighteen hundred and thirty six.

Witness,

R. H. Howell, *Notary Public*
